UNITED STATES PATENT OFFICE.

EARL C. HANSON, OF LOS ANGELES, CALIFORNIA, ASSIGNOR TO TITLE INSURANCE AND TRUST COMPANY, A CORPORATION OF CALIFORNIA.

WIRELESS TRANSMISSION OF ENERGY.

1,315,197.

Specification of Letters Patent. Patented Sept. 2, 1919.

Continuation of application Serial No. 49,287, filed September 7, 1915. This application filed May 25, 1918. Serial No. 236,944.

To all whom it may concern:

Be it known that I, EARL C. HANSON, a citizen of the United States, residing at Los Angeles, in the county of Los Angeles and State of California, have invented a new and useful Improvement in Wireless Transmission of Energy, of which the following is a specification.

My invention relates to the transmission of energy by means of electro-static and electro-magnetic induction from place to place without the use of wires or other conducting members. It differs essentially from previous attempts at such transmission in that it employs waves at audio frequency rather than the common type of waves which are of radio frequency. The audio frequency electro-static and electro-magnetic waves are those having a frequency within the range of the human ear, this frequency being below ten thousand cycles per second. The advantages of using the audio frequency are:

First: The simplicity of the apparatus employed.

Second: The freedom from interference with existing radio frequency installations.

Third: The freedom from atmospheric disturbances, and

Fourth: The possibility of controlling the range of the apparatus employed, thus allowing transmission to take place over limited distances without interference from or detection by similar apparatus outside the limited area involved.

This application is a continuation of my application, Serial No. 49,287, filed September 7, 1915.

In the drawing I represent diagrammatically a complete sending and receiving station. A single antenna 1 may be used, being connected to a switch 2 by means of which it may be connected to either a sending wire 3 or a receiving wire 4. Connected to the sending wire 3 is a reactor 5 having an iron core 6, whose position may be varied at will to vary the amount of reactance in the circuit. A series of contacts 7, each connected to a point in the winding of the reactor 5, is provided, and a movable arm 8 is also provided, so placed as to successively make contact with the contacts 7 by means of which the number of turns in the reactor 5 may be varied. The reactor 5 is connected through a wire 9 to one terminal

of the high tension winding 10 of an iron core transformer, the other terminal of the high tension winding 10 being connected through a wire 11 to a suitable ground 12. A low tension winding 13 of the same transformer is shunted by a variable condenser 14 and is connected through a wire 15 with a telephone transmitter 16, this transmitter being in turn shunted by variable condenser 17. The transmitter 16 is also connected through a wire 18 with one terminal of a battery 19 which is also shunted by a variable condenser 20. The other terminal of the battery 19 is connected through a wire 21 with a rheostat 22, which is in turn connected through a wire 23 with the other terminal of the low tension winding 13. The parts 5 to 23 inclusive form the sending apparatus above referred to.

The receiving wire 4 is connected through a movable arm 30 with any one of a series of contacts 31, each of which is connected to a portion of the winding of a reactor 32, this winding surrounding an iron core 33, the position of which may be varied with relation to the winding so that the amount of reactance may be varied. The other terminal of the reactor 32 is connected through a wire 34 with a switch 35, which is arranged to connect the wire 34 either with a wire 36 or with a wire 37. The wire 36 is connected through a telephone receiver 38 to the ground 12. The wire 37 is connected to the primary winding of a transformer 39 which forms a part of an amplifier, the other terminal of which winding is connected through a wire 49 with the ground 12. One terminal of the secondary winding of the transformer 39 is connected to the grid 43 of a vacuum bulb 40 which forms another part of the amplifier and has a filament 41 heated by a battery 42. The grid 43 is in intimate relationship to a plate 44 which is connected by means of a wire 45 with a battery 46, the other terminal of the battery 46 being connected through a wire 47 with a telephone receiver 48. The other terminal of the telephone receiver 48 is connected to the secondary of the transformer 39 through a wire 50.

The method of operation of the apparatus is as follows:

When it is desired to send a message, the switch 2 is used to connect the wire 3 with the antenna 1. With the apparatus so con-

nected, a current will flow from the battery 19 through the wire 18, transmitter 16, the wire 15, low tension winding 13 of the transformer, the wire 23, the rheostat 22 and the wire 21 back to the battery. This direct current being of practically constant strength will, of course, induce no current in the high tension winding 10. Whenever the operator speaks into the transmitter 16, 10 he will vary the resistance in the transmitter and cause a variable current to flow through the low tension winding 13 of the transformer. Variations in this current will induce a current in the high tension winding 10 which is connected to the ground 12 and to the antenna 1, through the iron core inductions 5. A considerable and variable potential will therefore be impressed between the antenna 1 and the ground 12, and 15 this will act through space through the medium of electro-static and electro-magnetic induction on a similar antenna at the receiving station.

At the receiving station the switch 2 will 25 be utilized to connect the antenna 1 to the receiving wire 4. This receiving wire will be connected to the wire 34 through the reactor 32, the reactance of which may be varied at will by moving the iron core 33 or varying the number of turns in the winding or both. In some cases it will be sufficient to connect the wire 34 with the wire 36 by means of the switch 35, the variations in intensity produced by the transmitter 16 being audible in the receiver 38 as audible speech. In other cases it is 30 desirable to amplify these variations, in which case the wire 34 will be connected to the wire 37 of the amplifier. This amplifier 35 has the property of acting as an extremely accurate and sensitive relay, and the faint currents introduced therein through the wire 37 serve to control much heavier currents produced by the battery 46, these 40 heavier currents being readily audible in the receiver 48. The general theory of the amplifier is well understood and need not 45 be gone into herein.

It will be seen that my invention employs 50 iron core reactors both at the sending and receiving stations. By the use of these reactors I am able to operate efficiently, using waves of audio frequencies. Foreign vibrations which may be collected by the antenna 1 at the receiving station which 55 are above this frequency are eliminated by the iron core 33 of the reactor 32. As a result parties using my invention may operate in close proximity to radio stations 60 without interference with or from such stations. My invention is particularly useful in signaling from trains, or in carrying on telephone conversations over short distances, such as, for example, from front to rear 65 line trenches or from and to ships and aero-

planes. By suitable regulation of the various parts, the area over which speech may be transmitted may be easily regulated.

The invention upon which this application is based is broader than the specific 70 embodiment thereof which has been shown for the purpose of illustrating one of its uses, and I intend no limitations other than those imposed by the appended claims or by the art. 75

What I claim is:

1. The combination in an apparatus for transmitting audio-frequency energy through natural media, of sending means at the transmitting station for producing audio 80 frequency energy, a receiving station comprising a responsive device, receiving means by which said energy actuates said responsive device and an iron core reactor in circuit with the responsive device. 85

2. A combination as in claim 1 in which the sending means includes an iron core reactor so placed as to eliminate radio frequency waves from the waves emitted from the sending station. 90

3. The combination in an apparatus for transmitting audio frequency energy through natural media, of sending means at the transmitting station for producing audio frequency energy, an induction coil at the transmitting station, an earth connection to one terminal of the secondary of the induction coil, a conductor connected to the other terminal thereof through a variable iron core reactor, a receiving station comprising a responsive device, an earth connection to one terminal of the responsive device and a variable iron core reactor and a conductor connected to the other terminal of the responsive device. 95 100

4. The combination in an apparatus for transmitting audio frequency energy through natural media, of sending means at the transmitting station for producing audio frequency energy, a receiving station comprising means for the reception of audio frequency energy, a vacuum tube amplifier, a responsive device connected with the amplifier, an earth connection to one terminal of the amplifier and an extended conductor connected to the other terminal through a variable iron core reactor. 110 115

5. The combination in an apparatus for transmitting audio frequency energy through natural media, of sending means at the transmitting station for producing audio frequency energy, a receiving station comprising means for the reception of audio frequency energy, a telephonic amplifier, a telephone receiver connected therewith, an earth connection to one terminal of the amplifier and an extended conductor connected to the other terminal through a variable iron core reactor. 120 125

6. In a wireless receiving station, means 130

for receiving energy having a frequency not greatly in excess of speech frequency from natural media, a vacuum tube relay for amplifying said energy and a responsive device actuated by the amplified energy.

- 5 7. A wireless sending station adapted to produce energy, having a frequency not greatly in excess of speech frequency, a receiving station comprising means for receiving said energy, a vacuum tube relay amplifier and a responsive device actuated by the amplified energy.
- 10

8. In a wireless receiving station, means for receiving energy having a frequency not greatly in excess of speech frequency from natural media through an antenna, means including a vacuum tube for amplifying said energy and a responsive device actuated by the amplified energy.

In testimony whereof, I have hereunto set my hand at Los Angeles, California, this 16th day of May, 1918.

EARL C. HANSON.
